ENGINE

Roger K. Lee, Highland Park, Mich., assignor to
 Chrysler Corporation, Highland Park, Mich., a
 corporation of Delaware

Application September 25, 1936, Serial No. 102,484

6 Claims. (Cl. 123—173)

This invention relates to internal combustion engines and refers more particularly to improvements in engine cylinder head structures and parts associated therewith.

One object of my invention is to provide an improved and more efficient cylinder head structure of relatively light weight and low cost.

Another object of my invention is to provide a cylinder head structure having improved uniformity of cooling whereby heat transfer is uniform. By providing a cylinder head which in operation maintains uniform transfer of heat, improved performance and economy is effected for the engine with which it is used.

A further object of my invention resides in the provision of an improved cylinder head having an inherent relatively small degree of deflection for deadening the fuel mixture explosion by lowering the frequency of vibration of the cylinder head.

A still further object of my invention is to provide an improved cylinder head structure in which the combustion chamber wall or dome is formed in whole or in part as a stamping. I have further provided a novel composite cylinder head which is fabricated in an improved manner. Such structures are especially beneficial in connection with radial engines or engines having other cylinder arrangements affording ample seating and sealing space for the flanges of the cylinder heads.

Another object of my invention resides in the provision of a cylinder head structure incorporating a cooling medium tank, thereby providing for an improved relationship in a radiator and engine installation in the vehicle. Thus, the available frontal opening in the vehicle structure for receiving the radiator may be more efficiently utilized since none of this opening is restricted by the usual radiator tank. While I preferably locate the upper radiator tank on the engine, the lower tank also may be carried on the engine, if desired. Also, the engine, especially when of the radial type, may, by reason of my improvements, be positioned at a more desirable elevation relative to the radiator to compactly arrange these parts in the vehicle; filling the radiator is also facilitated by my improvements.

Other objects of my invention are to provide a cylinder head structure having a minimum of carbon accumulating tendency, thereby effecting improved economy and performance, and reduced servicing costs; to provide an improved cylinder head structure which permits finer accuracies to be maintained in its manufacture, thus allowing a higher compression ratio; and to provide an

improved cylinder head having improved uniformity of wall cross-section as compared with that of ordinary cast cylinder heads having the inherent casting difficulty of shifting cores.

Further objects and advantages of my invention will be more apparent from the following illustrative embodiments thereof, in which:

Fig. 1 is a fragmentary end elevational view of a radial engine with a portion of one cylinder thereof broken away to illustrate the details of my improved cylinder head construction.

Fig. 2 is a top plan view of my improved cylinder head.

Fig. 3 is a side sectional view of my improved cylinder head taken as indicated by the line 3—3 of Fig. 2.

Fig. 4 is a side sectional view of my improved cylinder head showing a slightly different construction.

Fig. 5 is a diagrammatic view of a radial engine and radiator assembly illustrating a further embodiment of my improved cylinder head construction.

Fig. 6 is a side view of the radial engine and radiator assembly shown in Fig. 5.

Fig. 7 is a side sectional view of my improved cylinder head taken as indicated by the line 7—7 of Fig. 5.

Referring to the drawings, I have illustrated my improved cylinder head and parts associated therewith in a radial type engine wherein the engine cylinders are radially disposed about the engine crankshaft. While my improvements are especially adapted for use with radial engines of any number of cylinders, I desire to point out that my improvements may, if desired, be used with other well known types of engines wherein the cylinders are positioned in various other well known arrangements. The engine cylinders are further preferably of the well known L-head type which is especially adapted for installation and removal of my improved cylinder head structure.

A top member or cylinder head 10 is removably seated on the outer face of each cylinder by a plurality of fasteners 11. Each cylinder head 10 is provided with a water jacket space 12 communicating with adjacent cylinder heads through a plurality of water jacket flanges 13 and water passages 14, passages 14 being affixed to the flange 13 by fasteners 15. A water outlet extension 16 is mounted on the top-most head 10^a and secured thereto by fasteners 17. Each cylinder head has a spark plug 18 associated therewith for firing

the charge in the cylinder in the well known manner.

The spark plug 18 is received in a threaded hole 19 communicating with a combustion chamber 20, best shown in Figs. 1 and 3. Threaded holes 21 are provided to receive the flanges 13 which extend inwardly to the water jacket space 12. The extension 16 has a passage therein cooperating with an aperture 22 in the dome portion 10 of the head 10^a, threaded holes 23 being provided around the outer edges of the aperture 22 to receive the fasteners 17 for securing the extension 16 thereto while holes 24 are provided around the outer edges of the head to receive the fasteners 11 for securing the head to the cylinder block 25.

These cylinder heads consist preferably of stamped sheet-metal members suitably held assembled by the well-known hydrogen-welding process. The head 10^a also is so constructed, its design being like that of the heads 10 except that the water outlet extension 16 has been incorporated, as aforementioned.

A wall member 26 providing the combustion chamber 20, best shown in Fig. 3, is formed of a single stamping. Secured to the wall member 26 is a casing member 27 formed of stampings and providing the cooling jacket space 12 therein.

The member 27 may be made of a lighter gauge of sheet metal than the member 26 as shown. Thus, although the member 26 usually will require a relatively heavy gauge of sheet metal to withstand the pressure of the igniting fuel gas, it is possible to use a lighter gauge for the member 27, and thereby effect more efficient cooling of the combustion chamber 20 as well as a saving in weight and space.

During the stamping operation in forming the member 27, the aperture 22^a and two other apertures 21^a for the flanges 13 are preferably formed. A threaded flange member 21^b is then welded, or attached by other suitable means, to each of the apertures 21^a to receive therein the flange 13. A reinforcing member 28 is welded over the aperture 22^a in the member 27 which has an aperture 22^b aligned with the aperture 22^a. The threaded holes 23 may then be produced to receive the fasteners 17.

The members 26 and 27 are then novelly united by bending the entire outer edge of the member 27 over the extreme outer edge of the member 26, as at 29. Thereupon the portion of the member 27 in direct contact with the member 26, which portion extends completely around the outer portion of the member 26, as substantially shown at 30, is hydrogen-welded thereto.

The holes 24 and an aperture 19^a to receive therein a threaded thimble 19^b may then be drilled or stamped through both of members 26 and 27. This may be followed by inserting the thimble 19^b into the aperture 19^a and securing preferably during said welding. The thimble 19^b has a tight fit on assembly to clamp the member 27 with member 26 and to also facilitate the weld 35 at this point.

Referring now to the operation of my improved cylinder head, when the radial engine illustrated in Fig. 1 is operating, hot water flows from the heads 10 upwardly toward the head 10^a, entering therein through water passages 14 and flanges 13. Thereupon the water passes upwardly through the water jacket space 12 of the head 10^a toward the extension 16 and thence to the usual radiator (not shown).

75 The composite construction of my cylinder

head, especially the forming of the member 27 of a lighter gauge than that of the member 26, provides uniform and rapid transfer of heat. Improved performance and economy is thereby effected for the engine.

By using a sheet-metal stamping for the member 26, a relatively small degree of deflection therein is provided in the portion forming the combustion chamber 20. This deflection substantially deadens the fuel mixture explosion by lowering the frequency of vibration of the cylinder head.

The metal forming the combustion chamber in cast cylinder heads has greater surface porosity and natural roughness of surface than any sheet-metal members which would ordinarily be used in forming the combustion chamber 20 of my cylinder head. Thereby a cylinder head structure is provided which has a minimum of carbon accumulating tendency. Furthermore, in an internal combustion engine there is a greater tendency for carbon to accumulate on oxide scales such as are common in cast members, but not in stamped sheet-metal pieces.

Inasmuch as my cylinder head has a stamped sheet-metal combustion chamber, finer accuracies can be maintained in its manufacture than that of cast members. Hence my invention allows relatively higher compression ratios by reducing the permissible limits to a minimum in mass production.

Furthermore, my stamped sheet-metal cylinder head has improved uniformity of wall cross section as compared with that of ordinary cast cylinder heads having the inherent casting difficulty of shifting cores.

Referring to Fig. 4, I have shown another embodiment of my cylinder head, the construction and operation being substantially the same as that illustrated in the earlier described embodiment, the only difference being that the member 26 of Fig. 3 is formed in Fig. 4 of two stamped members welded together. The portion 26^a of the member 26^b forming the combustion chamber 20 is stamped separately from the flat portion 26^b of the member 26^b. The portion 26^a has a tight fit with member 26^b on assembly thereof to assist in holding these parts together and in facilitating the weld therebetween. After assembly of these parts they are then hydrogen-welded together, or suitably joined by other means, the weld extending entirely around the extreme outer portion of the combustion chamber portion 26^a, as at 31. This construction permits, if desired, the use of less complicated stamping dies than that for the Figs. 1, 2 and 3 structure. It also permits using a lighter gauge of sheet-metal for the flat portion 26^b than is used for the portion 26^a, thereby effecting a saving in weight and cost.

Referring now to Figs. 5, 6 and 7, I have shown still another embodiment of my cylinder head, the construction and operation being substantially the same as that illustrated in the earlier described embodiments, and I have indicated members of different construction but similar function by primed reference characters.

The radial engine cylinder block 25 is mounted rearwardly of a cooling radiator 32, this block having removably seated on its top-most cylinder a cylinder head 10^{aa}, the other heads 10 being identical to head 10 in Fig. 1. The head 10^{aa} is provided with a cooling medium tank or reservoir member 27' which is positioned higher than the radiator 32 and communicates with ad-

jaçent cylinder heads 10 through the water jacket flanges 13 and water passages 14.

The water outlet extension 16' is mounted on the forwardly side portion of the head 10^{aa} and secured thereto by welding and a plurality of the fasteners 17' and communicates with the radiator 32.

Head 10^{aa} has the spark plug 18 associated therewith for firing the charge in the cylinder in the well known manner.

A removable filler cap 33 is mounted atop the head 10^{aa} for supplying water to the cooling system of the engine.

The member 26 forming the combustion chamber 20 is identical with the Fig. 3 construction but the casing member 27 of Fig. 3 has been replaced by the stamped reservoir member 27' which is large enough to function as the cooling medium tank used in most liquid cooling systems.

The threaded flange members 21^b, the reinforcing member 28', the threaded thimble 19', and the members 26 and 27' are hydrogen-welded, or suitably joined by other means, to their respective positions of Fig. 7 substantially as previously explained for the Fig. 3 construction.

A filler neck 34 is welded, or attached by other suitable methods, to the member 27' and threaded at its other end to receive thereon the filler cap 33.

Mounted between the lower portion of the radiator 32 and the block 25 to communicate therebetween is a conduit 35, one end thereof being connected to a radiator outlet 36 and the other end being received by the block 25 which, if desired, may have a suitable water pump to impel the cooling medium through the cooling system. The conduit 35 is thus adapted to cooperate with the extension 16' in completing the engine cooling system.

With reference to the operation of the cooling system of Figs. 5, 6, hot water flows upwardly from the lower heads 10 to the reservoir member 27', entering therein through the passages 14 and flanges 13, from whence it passes through the extension 16' to the radiator. Additional cooling medium may be added to the system through the neck 34.

By incorporating the reservoir member 27' in the cylinder head 10^{aa} and above the level of the radiator 32, it is possible to lower and tilt the radiator as desired relative to its engine. Furthermore, such positioning will insure the maintaining of the cooling medium level above the level in the radiator 32. There will be a natural thermo-syphoning action even when a cooling medium pump is not provided or when the engine is inoperative, and it will not be possible to trap air in the engine or the radiator 32.

With the arrangement illustrated, the available frontal opening in the vehicle structure for receiving the radiator may be more efficiently utilized since none of this opening is restricted by the usual upper radiator tank. Also, the engine, especially when of the radial type, may be positioned at a more desirable elevation relative to the radiator to compactly arrange these parts in the vehicle; filling the radiator is also facilitated by my improvements.

I furthermore do not limit my invention, in the broader aspects thereof, to any particular combination and arrangement of parts such as shown and described for illustrative purposes, since various modifications will be apparent from the teachings of my invention and scope thereof as defined in the appended claims.

What I claim is:

1. In combination, an internal combustion engine of the radially arranged cylinder type comprising a plurality of wall members each providing a combustion chamber for a respective cylinder, a casing member secured to each of said wall members and providing a cooling jacket therefor, and a radiator for said engine, one of said casing members providing an upper tank for said radiator. 5

2. In combination, an internal combustion engine having a plurality of radially arranged cylinders, a head structure for each of said cylinders, each of said head structures including a water jacket, and cooling means for said engine comprising a radiator communicating with said water jackets, one of said cylinders being disposed adjacent one end of said radiator and having its water jacket of relatively great capacity with respect to the other of said water jackets to provide a tank for said radiator. 10 15

3. In combination, an internal combustion of the radially arranged type including a plurality of cylinders each having a cylinder head, cooling means for said engine including a radiator, a water jacket for each of said heads communicating with said radiator, one of said cylinders being disposed adjacent one end of said radiator and having its water jacket of relatively great capacity with respect to the other of said water jackets to 20 25 constitute a tank for said radiator, said last named jacket being positioned higher than said radiator and engine. 30

4. In an internal combustion engine including a plurality of cylinders, a cylinder head structure for each of said cylinders, each of said structures including a stamped metallic wall member having marginal portions, each of said wall members having a raised portion intermediate said marginal portions providing a combustion chamber for the adjacent cylinder, and stamped metallic casing members secured to said marginal portions of a respective wall member and spanning the raised intermediate portion of the latter, each of said casing members constituting a cooling jacket for the adjacent combustion chamber, the raised portion of each of said wall members being free from engagement with that portion of its casing member spanning said combustion chamber for accommodating limited deflection of said raised portion in response to forces created by the explosion of fuel mixture in said combustion chamber. 40 45 50

5. In an internal combustion engine including a plurality of cylinders, a cylinder head structure for each of said cylinders, each of said structures including a stamped metallic wall member having marginal portions and an opening intermediate the latter, a stamped wall member extending into said opening and providing a combustion chamber for the adjacent cylinder, and stamped metallic casing members secured to said marginal portions of said first mentioned wall members respectively and constituting a cooling jacket for the adjacent combustion chamber, each of said casing members having a portion thereof spanning a respective combustion chamber, each of said last named portions being free from engagement with its adjacent combustion chamber forming wall member to 60 65 70 the extent of freely accommodating a limited deflection of said latter member in response to forces created by the explosion of fuel mixture in said combustion chamber.

6. In an internal combustion engine including 75

a cooling system and a plurality of cylinders, a cylinder head structure for each of said cylinders, each of said structures including a wall member having marginal portions and a raised portion providing a combustion chamber for the adjacent cylinder, and stamped metallic casing members secured to the marginal portions of a respective wall member and spanning the raised portion of the latter, each of said casing members constituting a cooling jacket for the adjacent combustion chamber, one of said casing members

providing a reservoir for said cooling system, the raised portion of each of said wall members being free from engagement with that portion of its casing member spanning said combustion chamber for accommodating limited deflection of said raised portion in response to forces created by the explosion of fuel mixture in said combustion chamber and for unrestrictedly accommodating the flow of a cooling medium for said cooling system.

5

ROGER K. LEE.
